(57) **CLAIM**

The ornamental design for a transportation bag, as shown and described.

DESCRIPTION

FIG. 1 is a perspective view of a transportation bag;
FIG. 2 is a front view thereof;
FIG. 3 is a top view thereof;
FIG. 4 is a right side view thereof;
FIG. 5 is a left side view thereof;
FIG. 6 is a rear view thereof;
FIG. 7 is a bottom view thereof; and,
FIG. 8 is a sectional view taken along line 8A of FIG. 5 from 8B to 8C.

The broken lines depict environmental subject matter only and form no part of the claimed design.
